UNITED STATES PATENT OFFICE.

FLORENTIN KASANTZEFF, OF BERLIN, GERMANY.

AIR BRAKE OF THE ONE-LINED TYPE.

Application filed July 21, 1926. Serial No. 124,032.

The invention relates to an air brake of the one lined type, as especially used in rail-ways.

The invention essentially consists in avoiding the inaccuracies of the braking effect, arising especially in long trains in consequence of the circumstance that the governing pressure differences in the train pipe can only be relatively small, by bringing into action the governing pressure differences in the distributor in a relatively enlarged degree, especially by opposing to said modulated pressures an always constant pressure, so that the movable parts of the distributor very precisely follow the slightest pressure alterations and accordingly very precisely produce the different degrees of braking or brake lifting actions.

Further details of the invention are later described.

In the drawing a sample is shown:

Figure 1 is a diagrammatic view of the brake parts arranged on a wagon, and

Fig. 2 is a longitudinal section of the distributor and ruling device.

On the locomotive or other tractor the usual appliances may be arranged, such as an air pump, a main air container and a leader's valve, which serve for producing and maintaining any desired pressure in the train pipe 4, running along the cars or wagons to the brake.

On a wagon, an auxiliary container 6 and a brake cylinder 9 are arranged in usual manner, and by pipes 65 and 66 these parts and a combined distributor and ruling device are connected as shown in Fig. 1 to each other and to the train pipe 4.

According to Fig. 2 the parts of the combined device are the following. A feed valve 5 is connected to the pipe 65 and to the train pipe, and a channel 11 leads from said feed valve to an air chamber 37 of a distributor, comprising three diaphragms 38, 39, 40 with interposed chambers 58 and 59, said diaphragms being fastened to a spindle 74, which in known manner governs a double valve 47 arranged as shown for admitting air from the chamber 37 to the chamber 63 adjoining the smallest diaphragm 40 or exhausting air from said chamber to the atmospheric chamber 58. The chamber 59 included between the smaller diaphragms 39 and 40 is connected to a valve cone 60, which has an atmospheric channel 61 and a connecting channel 62

adapted for connecting the space 59 to the chamber 63 and the brake cylinder 9.

In the shown position of the valve cone 60 a strong braking action is obtained, as needed for loaded wagons, as follows.

The intermediate chambers 58 and 59 being open to the atmosphere, the whole area difference of the greatest diaphragm 38 and the smallest diaphragm 40 is effective for the movement of the diaphragm system, and therefore strong pressure differences and corresponding strong braking actions are produced by the chamber 63. When the valve cone is turned so as to connect the spaces 59 and 63, a weaker braking action is obtained due to the smaller difference of the area of the now acting diaphragms 38 and 39; this position is used for unloaded wagons. In each case the double valve 47 has the action of admitting or exhausting air to or from the chamber 63 and the brake cylinder.

The ruling device, combined with the distributor, is the following. A chamber 70, adjoining to the outer face of the greatest diaphragm 38, is connected by a channel 71 to the train pipe 4 by chamber 72 and pipe 65. This chamber 70 is closed by a still greater diaphragm 73, which is connected to the spindle 74 united all the diaphragms 73, 38, 39, 40. A further chamber 75, adjoining the outer face of the large diaphragm 73 is filled up with an always constant pressure from the auxiliary container through the pipe 66 and a channel 76, under the action of a constant pressure valve 77. This valve is of the usual double valve type with a governing diaphragm 78, closing the chamber 75 against an atmospheric chamber 79, and with a loading spring 80.

The action is the following. When for braking the train pipe pressure is diminished, the correspondingly diminished pressure in the chamber 70, due to the area difference of the diaphragms 38 and 73 causes the entire system to move against the accelerating chamber 37 under the constant pressure in chamber 75, whereby air from the accelerating chamber 37 and from the auxiliary container and train pipe is allowed to pass into the brake cylinder to such an extent as to restore the balanced primary position of the diaphragm system. When inversely the train pipe pressure is augmented, the inverse actions take place with the effect of lifting the brake to any desired degree.

The chamber 37 serves for furnishing a certain quantity of air for quickly applying the brake blocks to the wheels, to be braked, and further for smoothing the braking action by throttling the air streaming from the auxiliary container to the brake cylinder. For this purpose a small passage 90 is provided between the auxiliary container pipe 66 and the chamber 37, whereas a larger passage 91 is provided between the feed valve 5 and the chamber 37, so that the filling action of the train pipe is not diminished.

I claim:

- 15 1. An air brake of the one lined type, comprising in combination a train pipe, a brake cylinder, an auxiliary container, a distributor for admitting and exhausting air to and from said brake cylinder, a piston like acting member in said distributor and means for loading said member on one side by train pipe pressure and on the other side by a constant pressure greater than atmospheric pressure.
- 20 2. An air brake of the one lined type, comprising in combination a train pipe, a brake cylinder, an auxiliary container, a distributor for admitting and exhausting air to and from said brake cylinder, a piston like acting member in said distributor and means for loading said member on one side by train pipe pressure and on the other side by a constant pressure greater than atmospheric pressure.
- 25 3. An air brake of the one lined type, comprising in combination a train pipe, a brake cylinder, an auxiliary container, a distributor for admitting and exhausting air to and from said brake cylinder, a piston like acting member in said distributor and means for loading said member on one side by train pipe pressure and on the other side by a constant pressure greater than atmospheric pressure and a second piston like member, operatively connected to said first member, and loaded by the brake cylinder pressure in opposite direction to the action of said constant pressure.
- 30 4. An air brake of the one lined type, comprising in combination a train pipe, a brake cylinder, an auxiliary container, a distributor for admitting and exhausting air to and from said brake cylinder, a piston like acting member in said distributor and means for loading said member on one side by train pipe pressure and on the other side by a constant pressure greater than atmospheric pressure.
- 35 5. An air brake of the one lined type, comprising in combination a train pipe, a brake cylinder, an auxiliary container, a distributor for admitting and exhausting air to and from said brake cylinder, a piston like acting member in said distributor and means for loading said member on one side by train pipe pressure and on the other side by a constant pressure greater than atmospheric pressure and a second piston like member, operatively connected to said first member, and loaded by the brake cylinder pressure in opposite direction to the action of said constant pressure and an air chamber adapted to be connected through said double valve to the space adjoining said second member loaded by the brake cylinder pressure.
- 40 6. An air brake of the one lined type, comprising in combination a train pipe, a brake cylinder, an auxiliary container, a distributor for admitting and exhausting air to

and from said brake cylinder, a piston like acting member in said distributor and means for loading said member on one side by train pipe pressure and on the other side by a constant pressure greater than atmospheric pressure, and a second piston like member, operatively connected to said first member and loaded by the brake cylinder pressure in opposite direction to the action of said constant pressure, and a double valve operatively connected to said members so as to admit and exhaust air to and from the space adjoining said second member loaded by the brake cylinder pressure.

7. An air brake of the lined type, comprising in combination a train pipe, a brake cylinder, an auxiliary container, a distributor for admitting and exhausting air to and from said brake cylinder, a piston like acting member in said distributor and means for loading said member on one side by train pipe pressure and on the other side by a constant pressure, a double valve connected to said members so as to admit and exhaust air to and from the space adjoining said second member loaded by the brake cylinder pressure, and a second piston like member, operatively connected to said first member, and loaded by the brake cylinder pressure in opposite direction to the action of said constant pressure and an air chamber adapted to be connected through said double valve to the space adjoining said second member loaded by the brake cylinder pressure.

8. An air brake of the one lined type, comprising the parts enumerated in claim 4, the said air chamber being connected to said auxiliary container by a smaller passage than to said train pipe.

In witness whereof I affix my signature.

FLORENTIN KASANTZEFF
